UNITED STATES PATENT OFFICE.

WILLIAM PERRY MARTIN, OF BETHELRIDGE, KENTUCKY.

JAR CLOSURE OR SEALING DEVICE.

SPECIFICATION forming part of Letters Patent No. 623,326, dated April 18, 1899.

Application filed May 4, 1898. Serial No. 679,730. (No model.)

To all whom it may concern:

Be it known that I, WILLIAM PERRY MARTIN, a citizen of the United States, residing at Bethelridge, in the county of Casey and 5 State of Kentucky, have invented a new and useful Jar Closure or Sealing Device, of which the following is a specification.

This invention relates to fruit and other jars and more particularly to the closures or sealing devices of such receptacles.

My object is to provide a closure of improved construction capable of easy adjustment and affording a perfectly air-tight seal for the jar, which will evenly distribute the pressure on 15 the mouth of the jar incident to its attachment thereto in such a manner that all tendency toward cracking will be reduced to a minimum, if not entirely obviated.

The present invention is of the general type 20 of jar-closures comprising a cover to fit the mouth of the jar, a cap extending above the cover and attached to the jar-mouth, and a screw on the cap for holding the cover in closing position. Its component parts are, 25 however, of improved construction in various respects, whereby the objects heretofore set forth are attained; and the novelty of the invention resides in the improved features and novel combinations of parts fully described 30 hereinafter and particularly embodied in the appended claims.

In the accompanying drawings, Figure 1 is 35 a vertical section of my improved jar and closure, and Fig. 2 a detail plan view of the cap.

The jar 1, to which my improved closure is applied, is of the same construction as an ordinary fruit-jar with the exception of its mouth, which is enlarged or thickened on its 40 interior into the bead 2, having its upper face inclined, as shown at 3. The thickening at this point is for the purpose of giving greater strength at the part where the pressure is greatest. The usual screw-threads 4 are provided on the exterior of the neck, which is here curved slightly to more perfectly conform 45 to the shape of the cap.

The cover 5 is of dish or dome shape and preferably of glass or porcelain of suitable 50 thickness to stand considerable pressure. Its lower annular edge is beveled to correspond to the bevel on the jar which it is designed

to fit, a rubber gasket 6 being interposed between the two surfaces to insure a perfect and air-tight joint. A small undercut cavity is 55 provided in the upper outer portion of the cavity, which is filled with Babbitt metal 7 as a bearing for the tip of the clamping-screw on the cap.

The cap 8, which is of dome shape, may be 60 constructed out of any suitable metal having the necessary strength and a proper degree of resiliency, so that it will give without wrinkling or bending when under pressure. Its lower portion is provided with interior 65 screw-threads 8', designed to engage those on the jar. The cap is provided with a number of evenly-spaced integral ribs 9 on its exterior, which begin at the apex 10 where the cap is thickened and extend radially down to 70 about the line of the screw-threads. These ribs are arched and taper at their ends 11 and are highest (considered outwardly from the face of the cap) at points intermediate said ends, thus giving a construction which is both 75 light and strong. Besides being of practical value and constituting a valuable part of the invention they give it a symmetrical and pleasing appearance. The tightening or clamping screw 12 has a ring for the fingers 80 of the operator, and its shank is threaded through the part 10 in position for its tip to bear on the metal filling 7.

In sealing the jar the gasket is first applied to the beveled mouth and the cover then fit- 85 ted onto the gasket. The cap is then screwed on the jar over the cover and the clamping-screw turned until the cover is pressed down sufficiently to properly seal the jar. When the screw is turned and the cover pressed 90 against the jar-mouth, the pressure transmitted through the cover to the jar approximates a lateral direction, and were the cap not employed there would be a tendency toward expansion and breakage of the jar-neck 95 if the screw were turned too tight. The reactive pressure through the cap, together with the thickening of the jar-mouth, neutralizes this tendency, however. When the screw is turned, the upper portion of the cap is urged 100 away from the cover to a certain extent, as the reactive pressure on the cap will of course equal the active pressure on the cover. This reactive pressure being transmitted through

the cap equally in all directions from the apex is applied to the outer face of the jar-neck where the cap is screwed on, and acting in opposition to the pressure through the 5 cover practically neutralizes it, and thus prevents expanding and breakage of the jar-neck, so that the cover can be clamped down very tight to insure a perfect seal. The utility of the ribs on the cap is therefore apparent. They make possible the employment of a cap, which while light and sufficiently 10 springy is sufficiently strong. The thickening or beading of the mouth of the jar also affords a broad bearing-surface for the cover, 15 thus giving a better joint.

Having thus described my invention, what I claim as new, and desire to secure by Letters Patent, is—

1. The combination with a jar, of a cover 20 therefor, a cap having connecting means whereby it can be fastened to the jar, said cap housing the cover, a plurality of strengthening-ribs on the cap which radiate from its apex or top and extend down its sides, and a 25 clamping-screw adapted for exerting direct pressure on the cover and reactive pressure on the cap.

2. The combination with a jar having exterior screw-threads, of an arched cover for 30 the jar, a dome-shaped metallic cap, housing

the cover, which has screw-threads adapted to engage those on the jar and is provided with exterior, raised strengthening-ribs extending from its apex down its sides, and a clamping-screw passing through the apex 35 of the cap and adapted to hold the cover on the jar.

3. The combination with a jar having a flared or beveled mouth, and exterior screw-threads, of an arched cover having a beveled lower 40 edge adapted to fit the mouth, and provided with a bearing or seat in its apex, a gasket between the edge of the cover and mouth, a metallic, dome-shaped cap housing the cover which is provided with internal screw-threads 45 adapted to engage those on the jar and having exterior, raised, strengthening-ribs extending from its apex downward, and a clamping-screw threaded through the apex of the cap with its tip in position to abut the bearing or seat of the cover.

4. The herein-described dome-shaped cap having arched strengthening-ribs extending from its apex downwardly, said ribs tapering at their ends and being highest at their central points.

WILLIAM PERRY MARTIN.
